UNITED STATES PATENT OFFICE.

EDWARD H. REYNOLDS, OF CADILLAC, MICHIGAN, ASSIGNOR TO HIMSELF
AND WILLIAM CASSLER, OF SAME PLACE.

DESIGN FOR A FIRE-ESCAPE CLAMP.

SPECIFICATION forming part of Design No. 14,560, dated January 22, 1884.

Application filed May 3, 1883. Term of patent 14 years.

To all whom it may concern:

Be it known that I, EDWARD H. REYNOLDS, of Cadillac, in the county of Wexford and State of Michigan, have invented and produced a new and original Design for Fire-Escape Clamp, the same forming a new article of manufacture, of which the following is a specification, reference being had to the accompanying drawing, forming part thereof.

10 The figure represents a view in perspective of a fire escape clamp showing my new design.

My design relates to a novel configuration of fire-escape clamp; and it consists in a clamp of this description of an oblong rectangular figure on its exterior, and with the adjacent edges of its sections on either side of the clamp made to present a combined undulatory and straight configuration throughout the length of the clamp, as herein shown and described.

15 A A' indicate the two longitudinal sections or halves of the clamp, which is of an oblong rectangular figure on its exterior, and has the adjacent faces of its sections made to present

a combined undulatory and straight configuration on their exposed edges down or throughout the length of the clamp, on either side of it, such marginal contour consisting of a series of straight lines, s s, interrupted by convex lines m m, for the one section or half of the clamp, and a corresponding series of straight lines, n n, for the other section or half of the clamp.

20 I claim—

The design for a fire-escape clamp herein shown and described, the same presenting an oblong rectangular figure on its exterior, with the adjacent exposed edges of the sections A A' down either side of the clamp, making a combined straight and undulatory configuration consisting of a series of convex and concave lines, m n, united by straight lines s s.

EDWARD H. REYNOLDS.
